UNITED STATES PATENT OFFICE

2,280,279

WELL PUMP

Walter Brauer, Oklahoma City, Okla.

Application June 29, 1940, Serial No. 343,221

3 Claims. (Cl. 103—155)

This invention relates to improvements in deep well pumps and more particularly, but not by way of limitation, to an improvement in a rotary pump of the type shown in my prior Patent No. 2,171,171, issued on August 29, 1939.

An important object of this invention is to provide a pump which may be driven from the top of a well, and the construction is such that the pump can be put on tubing, run in the well and set with the tubing catcher. A string of rods can then be run through the tubing to provide a driving connection with the rotor of the pump.

A further object of the invention is to provide a deep well pump which can be operated by rotating the sucker rods, and as such rods may be readily guided in roller bearings, the rods will not be subjected to elongation due to reciprocation thus elimination rod stretch and breakage incident thereto. While the invention is shown using sucker rods, it will be apparent that any suitable string such as tubing, cable or the like, may be employed to rotate the rotor of the pump.

An additional object of this invention is to provide a pump which can be operated by rotating sucker rods and the construction is such that continuous rotation of the rods provides reciprocation of a plurality of sets of plungers or pistons provided in the pump.

And an additional object of this invention is to provide a pump which can be operated by rotating the sucker rods of the well, and the construction is such that the sucker rods rotate a tubular drive shaft having disposed therein a plurality of grooved spools rotating simultaneously with the drive shaft, said spools connected with a plurality of plungers adapted to reciprocate during rotation of the spools.

A further object of this invention is to provide a pump which can be operated by rotating the sucker rods of the well, and the construction is such that the sucker rods rotate a tubular drive shaft having a plurality of simultaneously rotating spools connected to a plurality of sets of plungers adapted to reciprocate during rotation of the shaft, and a set of valves cooperating with each set of plungers of such construction to allow natural flow of fluid therethrough.

A further object of this invention is to provide a pump which can be operated by rotating the sucker rods of the well and the construction is such that the rods may be readily received in a recessed driving connection of the pump to assure a better driving engagement and more efficient rotation of the rotor of the pump.

A further object of this invention is to provide

a compact pump which can be used in smaller sized casing, and of such construction that all parts run in oil at all times.

Other objects and advantages of the invention will be evident from the following detailed description read in conjunction with the accompanying drawings which illustrate one form of my invention.

In the drawings:

Fig. 1 is a fragmentary vertical sectional view partly in elevation of the upper portion of the pump.

Fig. 1A is a similar view of the lower portion of the pump.

Fig. 2 is a vertical sectional view of the lower portion of a well showing my improved pump disposed therein.

Fig. 3 is a view taken on lines 3—3 of Fig. 2.

Fig. 4 is a fragmentary vertical sectional view taken on lines 4—4 of Fig. 5.

Fig. 5 is a view taken on lines 5—5 of Fig. 1 with certain parts omitted for clarity.

Referring to the drawings in detail, 2 designates a string of casing, 4 a string of tubing and 6 the rod string of the well. The rod string extends from the top of the well where it is supported and driven by any suitable prime mover (not shown) functioning to rotate the rod string. The surface structure disclosed in my prior Patent No. 2,171,171 is adequate for this purpose.

At various points along the rod string I employ antifriction bearings 8 (only one of which is shown in Fig. 2) having radially extending wings 10 adapted to abut against the tubing 4 for centering the rod string and prevent contact with the inner wall of the tubing.

The lower end of the tube is provided with a tubing catcher 12 of any conventional type which may be set from the top of the well in order to anchor and support the tubing 4. A sleeve 14 is provided with left hand threads 16 for receiving similar threads at the lower end of the tubing string as indicated at 18. The sleeve 14 is provided with exterior threads as shown at 20 for a threaded connection with annular collar 22, which in turn is threaded at 24 with an axially extending cylindrical member or casting 26. Disposed within the cylinder 26 is a tubular drive unit 28 anchored at its upper end by roller bearing or race 30. The tubular unit comprises an upper cylinder 32 and a lower cylinder 33. The upper cylinder 32 has a radially extending flange 34 for supporting the race 30.

A cylindrical drive connection 38 is interposed between the cylinders 32 and 33 and is secured

to the lower and upper ends of the cylinders respectively by any conventional means such as welding or the like. The drive connection 38 is provided with a recess 40 of irregular shape in cross section (preferably hexagon) (see Fig. 3) for receiving the lower end of the complementary hexagon shaped rod string 6 for a purpose as will be hereinafter set forth.

As shown in Figs. 1 and 1A, a collar 44 is threaded at 46 to the cylinder 26. A cylindrical housing or casing 48 is threaded at 50 to the collar 44 and extends axially into threaded engagement as shown at 52 with an internal tubular member 54. A lower casing 56 is threaded at 58 to the tubular member 54 and in turn is provided with internal threads 60 for receiving a "bull" plug 62 having a nut 64.

Alluding further to the drive unit 28, a collar 66 is secured to the lower end of the tubular shaft 33, and is provided with spaced projecting clutch teeth 68 cooperating with complementary clutch teeth 69 provided on a collar 70. The collar 70 is threaded at 72 to a second drive cylinder or tubular shaft 74 extending through the casing 48, tubular block 54 and lower casing 56.

The upper end of the drive cylinder 74 is slightly tapered providing a friction tight engagement for a spool 76 disposed thereon. A pin and slot connection 78 prevents rotative movement of the spool on the drive cylinder 74. An anti-friction roller bearing 80 is held in adjusted position by nut 81 and prevents longitudinal displacement of the spool on the drive cylinder 74. The nut 81 is threaded as shown at 82 to the casing 48.

The spool 76 is provided with an angled groove 83 of substantially spiral shape for a purpose as will be hereinafter set forth. A similar spool 76' is arranged at the tapered lower end of the shaft 74. However, the spiral groove 83' for the lower spool is in an opposite direction to that of the groove provided in the spool at the upper end of the shaft. A lower bearing or race 88 and adjusting nut 90 anchors the lower end of shaft 74.

The internal tubular member 54 is provided with a set of bores 92 (preferably 6) (Fig. 5) arranged symmetrically about the axis of the pump. The bores are adapted to receive sets of upper and lower plungers 94 and 96 respectively (preferably six sets or twelve plungers), the construction being such that the plungers in each aligned bore move away from one another to draw liquid into the bores as will be hereinafter set forth. As clearly shown in Figs. 4 and 5, the tubular member 54 is provided with a second set of bores 98 (preferably 6) arranged symmetrically about the axis of the pump and in spaced relation to the bores 92. An intake ball valve 100 and a discharge ball valve 102 cooperating with valve seats 104 and 106 respectively are arranged in each of the bores 98. The lower portions of each of the bores 98 are provided with a plug 99. The bores are drilled through the blocks 54 to facilitate removal of the seats 104 and 106. The internal member 54 is provided with a plurality of circumferentially spaced transverse ports 110 communicating with the valve bores 98, to allow for flow of fluid from the well into the pump. Communication between the piston bores and the valve bores is provided by a plurality of ports 112. For manufacturing simplicity the ports 112 are formed by drilling radial apertures in the internal tubular member 54 to such a point where each set of bores 92 and bores 98 are brought into communica-

cation. A plug 116 is inserted in each aperture 114 to prevent discharge of fluid from the member 54.

A connecting rod 118 is secured to each of the plungers 94 and 96 by a threaded connection as shown at 120. The connecting members 118 are each formed with a projection 122 engaging a plurality of annular ball bearings or races 124 disposed within the spiral grooves 83 and 83' for the spools 76 and 76' respectively. It will be understood that there is a corresponding number of ball bearing races 124 in the groove of each spool to the number of connecting rods 118 and plungers cooperating with a particular spool. It will be obvious that rotation of the spools 76 and 76' by means of the drive unit 28 and shaft 74 will cause the plungers 94 and 96 to reciprocate.

Operation

The pump after being attached to the lower end of the tubing can be run into the well, and at the desired depth the pump may be set by operation of the tubing catcher 12. The rods are then run into the tubing and the lower section of the rod string is received in the recess 40 of the member 38 to provide a driving connection with the drive unit 28. The rods are then caused to rotate by the source of motive power at the surface of the well (not shown) with a simultaneous rotation of the hollow shafts 33, 74 and spools 76 and 76'. It will be understood that the pump is prevented from rotation by the tubing catcher. As the spools 76 and 76' rotate, a set of opposed plungers 94 and 96 in one instance will be moved away from one another to draw fluid through a port 110, intake valve 100, port 112 and into a respective cylinder 92. Due to the spiral configuration of the grooves 83 and 83', continued rotation of the spools causes the set of plungers to be moved toward one another to force oil from the bore 92 through the discharge valve 102 into the chamber 126. It will be understood that the intake valve 100 is closed during this latter operation. The fluid discharge will pass through apertures 128 into the hollow shafts 74 and 33 to be discharged through apertures 130 provided in cylinder 33, into chamber 132, then through apertures 136 upward through cylinder 32, collar 14 and travel up the tubing to the top of the well. It will be apparent that the arrangement of the intake and discharge valves is such to allow free discharge of fluid therethrough. This is advantageous in a natural flowing well having sufficient bottom hole pressure to lift the oil up the tubing in conjunction with the pump. A plurality of spaced apertures 134 are provided near the lower portion of shaft 74 in definite relation to apertures 128, assuring proper assembly of shaft 74 regardless of which end is inserted first, thus providing an outlet for discharge chamber 126. The apertures 134 also allow for flow of lubricant oil to adjacent rotating parts.

This invention employs small plungers, preferably one half inch in diameter having slight clearance so that no packing is needed and sand can not get between the piston and its bore. It will be understood that the grooves 83 and 83' are formed so that a set of plungers come together at the same time and provide a one inch stroke. The construction is such that in case a valve should become inoperative, only two plungers will stop pumping.

It will be observed that the construction pro-

vides a multiple plunger pump secured to the lower end of a tubing catcher with left hand threads, and as the tube is anchored to the casting, rotation of the drive shafts of the pump will not unscrew the tubing or pump. The pump has a plurality of small pistons driven by spools provided with angled grooves of substantially spiral configuration with respect to the drive shaft in order to give a lifting power similar to a screw jack, e. g., two threads per inch, thus giving a one inch stroke and allowing the use of only a single set of check valves for each set of aligned plungers. Furthermore, the pump is constructed so that additional pumping units can be added (for increasing production) by merely unthreading the nut 64 of plug 62 to allow engagement of the additional unit with the clutch teeth 69' of the shaft 74.

Changes may be made in the combination and arrangement of parts as heretofore set forth in the specification and shown in the drawings, it being understood that any modifications in the precise embodiment of the invention may be made within the scope of the following claims without departing from the spirit of the invention.

What I claim is:

1. A deep well pump comprising a tubular cylinder having a plurality of longitudinally arranged plunger bores, reciprocating plungers operating in the bores, a plurality of valve bores arranged in the cylinder in spaced relation on to the plunger bores, a combination intake and discharge valve structure arranged in the valve bores, means providing communication between the plunger bores and the valve bores, inlet means provided in the outer periphery of the cylinder and communicating with the valve bores, rotatable driving means extending through the cylinder and having upper and lower spools arranged thereon, a spiral shaped groove for each of the spools arranged in opposite directions to each other, a plurality of ball bearings arranged in each of the spool grooves, and means connected at the outer ends of each of the plungers and cooperating with the ball bearings for causing reciprocation of the plungers due to rotation of the driving means.

2. A deep well pump comprising a tubular cylinder having a plurality of longitudinally ar-

5 ranged plunger bores, reciprocating plungers operating in the bores, a plurality of valve bores arranged in the cylinder in spaced relation to the plunger bores, a combination intake and discharge valve structure arranged in the valve bores, means providing communication between the plunger bores and the valve bores, inlet means provided in the outer periphery of the cylinder and communicating with the valve bores, 10 rotatable driving means extending through the cylinder and having upper and lower spools arranged thereon, a spiral shaped groove for each of the spools arranged in opposite directions to each other, a plurality of roller bearings arranged in each of the spool grooves, means connecting at outer ends of each of the plungers and cooperating with the roller bearings for causing reciprocation of the plungers due to rotation of the driving means, said driving means being of tubular form and provided with means placing its interior in communication with the valve bores whereby the driving means functions as a conduit for the pumped liquid.

20 3. A deep well pump comprising a tubular cylinder having a plurality of longitudinally arranged piston bores, a plurality of valve bores arranged in spaced relation to the piston bores, a combination intake and discharge valve structure arranged in the valve bore, means providing communication between the piston bores and the valve bores, a plurality of inlet ports provided in the cylinder and communicating with the valve bores, rotatable driving means extending through the cylinder and having upper and lower spools 25 secured thereto, a spiral groove for each spool arranged in opposite directions to each other, reciprocating pistons operating in the piston bores, freely rotatable means arranged in the spiral grooves of the spools, and means secured at the outer ends of the pistons to operatively engage the freely rotatable means for causing reciprocation of the pistons due to rotation of the driving means, said driving means having two sets of apertures providing communication between the 30 interior of the driving means and the valve bores, said sets arranged in definite spaced relation to each other to assure proper assembly of the driving means.

35 4. A deep well pump comprising a tubular cylinder having a plurality of longitudinally arranged piston bores, a plurality of valve bores arranged in spaced relation to the piston bores, a combination intake and discharge valve structure arranged in the valve bore, means providing communication between the piston bores and the valve bores, a plurality of inlet ports provided in the cylinder and communicating with the valve bores, rotatable driving means extending through the cylinder and having upper and lower spools 40 secured thereto, a spiral groove for each spool arranged in opposite directions to each other, reciprocating pistons operating in the piston bores, freely rotatable means arranged in the spiral grooves of the spools, and means secured at the outer ends of the pistons to operatively engage the freely rotatable means for causing reciprocation of the pistons due to rotation of the driving means, said driving means having two sets of apertures providing communication between the 45 interior of the driving means and the valve bores, said sets arranged in definite spaced relation to each other to assure proper assembly of the driving means.

WALTER BRAUER.
